UNITED STATES PATENT OFFICE

2,656,770

AUTOMATIC PARTITION STRIP FEEDING
MECHANISMSimon E. Schroeder, Oshkosh, Wis., assignor to
American Partition Corporation, Milwaukee,
Wis., a corporation of Wisconsin

Application January 3, 1949, Serial No. 68,955

26 Claims. (Cl. 93—37)

1

The present invention relates generally to partition forming mechanisms, and more particularly to automatic feeding mechanism for delivering a set of partition strips to an assembly zone in position for interengagement by transverse partition strips supplied by a second mechanism.

An object of the present invention is to provide novel automatic feeding mechanism for supplying preformed partition strips to an assembly zone in position for reception of transverse partition strips supplied by a second mechanism, such as the partition assembling machine disclosed in the Vail and Dauber Patent No. 2,163,923, granted June 27, 1939.

Another object is to provide novel mechanism for automatically feeding preformed partition strips into an assembly zone which incorporates novel mechanism for releasing the bottommost strip of stacks of partition strips and for disposing the released strips in edgewise spaced relation for sliding longitudinal movement.

Another object is to provide novel mechanism for automatically feeding preformed partition strips into an assembly zone which incorporates guiding construction for an edgewise disposed partition strip whereby a second edgewise disposed strip may be moved into overlapping relation with a leading edgewise disposed strip.

Another object is to provide novel mechanism for automatically feeding preformed partition strips into an assembly zone which incorporates synchronized roller constructions for first moving an edgewise disposed partition strip at a substantially uniform rate towards an assembly zone, and then at a step by step rate through the assembly zone, and for moving a trailing edgewise disposed partition strip into overlapping relation with a leading edgewise disposed partition strip as the leading strip is moving in step by step relation through the assembly zone.

Another object is to provide novel mechanism for automatically feeding preformed partition strips into an assembly zone which incorporates a plurality of guideways for receiving partition strips in edgewise relation and for directing them into predetermined spaced parallel relation for movement towards and into an assembly zone.

Another object is to provide novel mechanism for automatically feeding preformed partition strips into an assembly zone which incorporates continuously moving spaced cross members for moving edgewise disposed partition strips towards an assembly zone along provided guideways and into engagement with rollers for mov-

2

ing the strips a second step towards the assembly zone, the cross members being disposed substantially at right angles across the path of movement of the strips for pushing abutment with the rear edges of the strips to align the same prior to transfer to the rollers.

Another object is to provide novel mechanism for automatically feeding preformed partition strips into an assembly zone incorporating actuating mechanism for releasing the bottommost strips of stacks of partition strips actuated by a provided device which moves edgewise disposed released strips towards an assembly zone.

Other objects are to provide novel mechanism for automatically feeding preformed partition strips into an assembly zone which is fully automatic in operation in the handling of preformed partition strips between hoppers and the assembly zone, which is simple in operation, which is capable of attaining a high efficient speed of operation, which is adjustable in its individual and composite mechanisms, which may be adjusted as to speed of handling partitions, which is adapted to function efficiently in its capacity of automatically feeding partition strips for a long period of time with only normal greasing, oil and cleaning maintenance, which incorporates a minimum number of moving parts, thereby reducing breakdown possibilities to a minimum, which is relatively inexpensive, which is easy to synchronize with an associated machine such as the assembling machine shown in the above-mentioned Vail and Dauber patent, which requires no instruction in respect to operation since the feed is fully automatic from the hopper compartments, which may be filled by hand or by other automatic means associated with stripper machine or other mechanism, and which may be supplied with an automatic alarm device for notifying an operator that a particular partition strip has failed to pass a designated point or is failing to pass a designated point.

The foregoing and other objects and advantages are apparent from the following description taken with the accompanying drawings, in which:

Fig. 1 is a side elevational view of a mechanism for automatically feeding preformed partition strips into an assembly zone constructed in accordance with the teachings of the present invention, the cover being removed from the gear box through which power is transmitted to the feeding rollers and the continuous chain of the mechanism (Sheet 1);

Fig. 2 is a plan view thereof (Sheet 2);

Fig. 3 is an end elevational view thereof, the gear box cover being shown removed and the power transmission shaft being broken away (Sheet 3);

Fig. 4 is an enlarged plan view of the roller feed and the partition strip guide constructions forming parts of the present invention (Sheet 4);

Fig. 5 is an enlarged fragmentary plan view of the rear portion of the conveyer and related platform constructions (Sheet 2);

Fig. 27 is an enlarged vertical longitudinal cross-sectional view on substantially the line 27—27 of Fig. 4 (Sheet 6);

Fig. 28 is an enlarged vertical longitudinal cross-sectional view on substantially the line 28—28 of Fig. 2 (Sheet 5);

Fig. 29 is an enlarged fragmentary vertical longitudinal cross-sectional view on substantially the line 29—29 of Fig. 2 (Sheet 3);

Fig. 30 is a vertical transverse cross-sectional view on substantially the line 30—30 of Fig. 29 (Sheet 3);

10 Fig. 31 is an enlarged fragmentary vertical longitudinal cross-sectional view on substantially the line 31—31 of Fig. 2 (Sheet 8);

Fig. 32 is an enlarged fragmentary vertical longitudinal cross-sectional view on substantially the line 32—32 of Fig. 2 (Sheet 8);

Fig. 33 is an enlarged fragmentary vertical longitudinal cross-sectional view similar to Fig. 31 in details disclosed, but with the trip shoe engaged by a transverse bar and the actuated valve in open position (Sheet 8);

Fig. 34 is an enlarged plan view of the pivotally supported mount for the trip shoe of Fig. 33 (Sheet 8);

Fig. 35 is an enlarged vertical transverse cross-sectional view on substantially the line 35—35 of Fig. 2 (Sheet 9);

Fig. 36 is a perspective view of one of the partition strip deflectors (Sheet 5);

Fig. 37 is a further enlarged view of an adjustable bracket member forming part of the mechanism for releasing the bottommost of a stack of preformed partition strips (Sheet 9);

Fig. 38 is a vertical longitudinal cross-sectional view on substantially the line 38—38 of Fig. 37 (Sheet 9);

Fig. 39 is a vertical transverse cross-sectional view on substantially the line 39—39 of Fig. 38 (Sheet 10);

Fig. 40 is an isometric view of a supporting plate (Sheet 10);

Fig. 41 is an isometric view of a spacer member (Sheet 10);

Fig. 42 is an isometric view of a blade member for moving the bottommost partition strip of a stack of the same into releasable position (Sheet 10);

Fig. 43 is an isometric view of a block member beneath which the blade member of Fig. 42 reciprocates (Sheet 9);

Fig. 44 is an enlarged vertical transverse cross-sectional view on substantially the line 44—44 of Fig. 35 (Sheet 9);

Fig. 45 is front elevational view of the base of a partition assembling machine, such as that illustrated in the above-mentioned Vail and Dauber patent, the feed end of the present automatic partition strip feeding mechanism being shown partially in elevation and partially in transverse cross section (Sheet 10);

Fig. 46 is a fragmentary side elevational view of the base shown in Fig. 45, the innermost pairs of feed rollers and the vertical adjustment mechanism being illustrated in side elevation (Sheet 10);

Fig. 47 is an enlarged horizontal cross-sectional view on substantially the line 47—47 of Fig. 45 (Sheet 10);

Fig. 48 is an enlarged vertical longitudinal cross-sectional view on substantially the line 48—48 of Fig. 45 (Sheet 10); and

Fig. 49 is a perspective view of a partition strip of the simple non-interlocking type (Sheet 4).

Referring to the drawings more particularly by reference numerals, 52 indicates generally an 75 automatic partition strip feeding mechanism

constructed in accordance with the concepts of the present invention. Broadly, the feeding mechanism 52 includes a frame 54 (Figs. 1-3), a hopper 56 (Figs. 1-3, 29, and 39), a partition strip release mechanism 58 (Figs. 29, and 37-42), partition strip edgewise disposing construction 60 (Figs. 3, 29 and 39), partition strip guide construction 62 (Figs. 1, 2, 4 and 22), partition strip conveyer construction 64 which includes a platform 66 and supporting construction (Figs. 1, 2, 6 and 28), a constant speed partition strip feed construction 68 (Figs. 4 and 15), a step by step partition strip feed construction 70 (Figs. 4, 13, 16 and 17), a drive mechanism 72 for the conveyer and constant feed constructions (Figs. 1, 2, and 7-10), and interrelated and interconnecting elements and members.

More specifically considering the present automatic feeding mechanism 52, the frame 54 includes four selectively spaced tubular posts 75 each of which is mounted in a pedestal 76 clamped to the posts by bolts extending through flanges 77 of a collar extension 78 (Figs. 1-3). Bolts 79 extend through an annular flange for anchoring each pedestal 76 to a suitable base 80. At the top of each post 75 is a three-way split clamp 82, each being secured to its respective post 75 by the usual nut and bolt assemblies extending through the vertical spaced flanges. Each clamp 82 supports an end of a transverse horizontal tubular frame member 84 and an end of a longitudinal horizontal tubular frame member 85. In similar manner, three-way split clamps 86 secured to each post 75 intermediate the ends thereof support intermediately disposed transverse horizontal tubular frame members 87 and longitudinal horizontal tubular frame members 88. A three-way split clamp 90 is secured to each frame member 85 intermediate the ends thereof and supports a vertical tubular frame member 94 intermediate the ends thereof, and a transverse horizontal tubular frame member 95 which is intermediate the frame members 84 and in the same horizontal plane therewith. At the upper end of each frame member 94 is a two-way split clamp 96, the two clamps 96 supporting a transverse horizontal tubular frame member 97. Near the lower end of each vertical frame member 94 is a two-way clamp 98 which is secured to the adjacent frame member 88. It is manifest that the frame 54 is sturdy.

The hopper 56 comprises a plurality of spaced vertical longitudinal wall members 100, each of which includes a split clamp 101 extending from the lower corner of the rear edge and split clamps 102 extending from the upper and lower corners of the front edge (Figs. 1-3, 29 and 39). Each wall member 100 includes a flange 104 secured to and extending at right angles from the front edge to provide front walls for open compartments 105 between the wall members 100 (Figs. 3 and 35). As illustrated, one wall member 100 does not include a flange 104, since it is obviously unnecessary. The wall members 100 are adjustable along the several supporting frame members and are spaced apart to accommodate partition strips of predetermined widths or heights. Each wall member 100, with the exception of the right-hand one, has a deflector plate 107 secured along the lower portion by suitable screws 108 (Figs. 3 and 39). Each plate 107 has a bevelled upper edge 109 for directing the individual partition strips 115 of a stack within the compartment 105 into the space between 75

the plate 107 and the opposed face of the opposite wall member 100.

Particularly considering the partition strip release mechanism 58 (Figs. 29, and 37-42), front and rear bearing blocks 110 and 111, respectively, are secured by suitable screws 112 to the bottom edge of each wall member 100 (Figs. 29 and 38). Each pair of bearing blocks 110 and 111 rotatably supports a shaft 113 which is retained against axial movement by collars 114 secured to the shaft 113 by suitable setscrews disposed against the outer face of each bearing block 110 and 111.

Adjacent each bearing block 110 and 111, and interiorly disposed relative thereto, is a composite housing 116 adjustably secured to the bottom edge of the respective wall member 100 by suitable screws 118 (Figs. 29, and 38 through 43). Each composite housing 116 holds a blade 117 and includes a block member 120 (Fig. 43) having a square centrally disposed opening 121 which is disposed against the bottom edges of the wall member 100 and the plate 107, one side of the block member 120 being flush with the vertical surface of the member 107 (Fig. 39). Below the block member 120 is a supporting plate 123 (Fig. 40) which is of greater width than the block 120 and which includes a central opening 124 and opposed bevelled edges 125. The supporting plate 123 is spaced from the block member 120 by spacer members 128 (Fig. 41). Manifestly, holes are provided in the block member 120, the supporting plate 123, and the spacer members 128 for reception of the screws 118. The blade member 117 (Fig. 42) includes a central opening 130 and is disposed between the block member 120 and the supporting plate 123 for limited movement (Figs. 38 and 39), being restricted against forward and rear movement by the spacer members 128. For moving the blade member 117 transversely of the wall member 100, there is provided an actuating member 132 secured to the shaft 113 by a suitable pin 133. The actuating member 132 includes a finger 134 which extends through the openings 124, 130 and 121 of the supporting plate 123, the blade member 117, and the block member 120, respectively. It is clear from Fig. 39 that the blade member 117 may be reciprocated by the actuating member 132 between the limits of the transverse dimension of the opening 121 of the block member 120, since the finger 134 will be stopped by opposed walls of the opening 121.

It is also clear from Fig. 39 that the opposed pairs of supporting plates 123 support stacks of partition strips 115 disposed within each compartment 105. It is to be understood that the thickness of the spacers 128 must be sufficient to permit a partition strip 115 to be moved beneath the inner edge of the block member 120 into the position illustrated in Fig. 39.

On the forward end of each shaft 113 is a rocker arm 138 secured against movement by a suitable pin 139, or the like (Figs. 37 and 38). A horizontal post 140 is secured to the free end of each rocker arm 138 by a nut 141 engaging a threaded reduced end thereof. A reciprocably mounted shaft 143 is supported adjacent the rocker arms 138 by split bearing brackets 144 and 145 secured to the frame member 95 (Fig. 35). The left end of the shaft 143 extends through an arm of a split bearing bracket 146 secured to the frame member 95 (Figs. 35 and 44) and has a post 148 mounted radially near the end thereof which extends into a slot 149

formed in the free end of a plate member 150 secured by suitable screws 151, or the like, to the bracket 146. A compression spring 152 surrounds the shaft 143 to the right of the arm of the bracket 146 and engages the bracket 146 at one end and an adjustable collar 153 at the other end, the collar 153 being secured to the shaft 143 by a suitable setscrew, or the like. The spring 152 biases the shaft 143 to the left as the mechanism 52 is viewed from the rear (Fig. 3).

The shaft 143 supports a plurality of U-shaped brackets 156 (Figs. 37 and 38), each of which includes a split sleeve portion 159 engaging the shaft 143 and being secured thereto by suitable nut and bolt assemblies 160. Each bracket 156 also includes aligned spaced internally threaded sleeves 162, each of which receives a threaded bolt 163, a lock nut 164 being employed to secure the bolt 163 in its selected position. A space 165 is defined by the opposed faces of the sleeves 162 which receives the free end of the post 140 and into which extend ends of the bolts 163. As is clear from Fig. 37, the ends of the bolts 163 are brought into substantial engagement with the post 140, and, hence, therethrough reciprocation of the shaft 143 will rock the rocker arms 138.

At its right end, the shaft 143 is in abutment with a plunger 166 which extends from an air cylinder 169 of conventional construction supported by a split bracket 170 secured to the frame member 95 (Figs. 32 and 35). An air supply line 171 leads into the air cylinder 169 from the exhaust side of a simple standard reciprocating air valve 173 secured by suitable screws, or the like, to a plate 174 secured to the lower end of a depending plate 172 which is formed integral with the lower half of clamp 145 (Figs. 3 and 31). An air supply line 175 leads into the intake side of the valve 173 from a source of air supply such as a compressor or the like (not shown). A plunger 176 is secured to the air piston of the air valve 173 and extends downwardly from a secondary casing 177. A suitable spring, or the like (not shown), located within the casing 177 biases the plunger 176 and the associated air cylinder into the position of Fig. 32.

A short shaft 180 is disposed beneath the plunger 176, being welded or otherwise secured to spaced straps 181 which are, in turn, secured by suitable screws, or the like, to a bar 182 having end trunnions 183 which engage openings in the upper ends of spaced vertically disposed twisted strap posts 184 secured by suitable bolts 185 to a plate forming part of the support for the platform 66 and more particularly described below (Figs. 32-34). A depending shoe 187 is secured to the shaft 180 through sleeves 188 and suitable setscrews, or the like. The shoe 187 is adjustable along the shaft 180 to determine its point of engagement by the conveyer construction 64 (described in detail below) for pivotal movement of the shaft 180 to move the plunger 176 upwardly to open the air valve 173 to supply air to the air valve 169. An angular hanger strap bracket 190 secured to the plate 174 by suitable screws, or the like, limits the downward pivotal movement of the shaft 180, the free end 191 extending horizontally beneath the shaft 180, as is clear from Figs. 32 and 33.

Beneath the hopper 56 is disposed the partition strip edgewise disposing construction 60 which comprises pairs of opposed longitudinally extend-

ing plates 195 and 196 (Figs. 2, 3, 6, and 29). Each plate 195 includes a vertical portion 197 and a horizontal portion 198 secured by suitable screws 199, or the like, to the bottom of the bearing blocks 110 and 111 depending from three wall members 100 counting from the left, viewing the mechanism 52 from the rear (Fig. 29). Each plate 196 includes a vertical portion 200, an angular portion 201, and a horizontal portion 202 also secured by the screws 199 to the bottom of the bearing blocks 110 and 111 depending from the three right-hand wall members 100. The relationship of the plates 195 and 196 to the compartments 105, and hence to partition strips 115 disposed therein is clearly shown in Figs. 3, 6 and 39. Considering Fig. 39, it is to be noted that a released partition strip 115 will strike the horizontal portion 202 of the plate 196 along its right longitudinal edge, whereupon the left side will fall by gravity, as indicated by the broken arrow A, which will result in the partition strip 115 assuming an edgewise position between the plate portion 197 and the plate portion 200.

Beneath and forwardly of the partition strip 60 is the partition strip conveyer construction 64 (Figs. 1 through 3, 5, 6, 28 and 29). Supporting the conveyer construction 64 are spaced longitudinally disposed channel-shaped side plates 206. As is clear from Figs. 6 and 28, the side plates 206 rest on the frame members 87 and are secured thereto by suitable U-bolt assemblies 207 which partially encircle the frame members 87 and extend through suitable openings in the lower flange of the side plates 206. The side plates 206 are further reinforced by transversely disposed channel bars 208 which are preferably welded to the underside of the lower flange of each side plate 206 (Fig. 28). A rear end plate 210 is welded or otherwise secured to the rear ends of the side plates 206 to protect an operator from the conveyer mechanism 64.

A forwardly disposed transverse shaft 212 is rotatably supported by bearings 213 mounted on the side plates 206 near the forward ends and preferably exteriorly thereof (Fig. 5). A second transverse shaft 216 is supported in bearings 217 which are adjustably mounted on the side plates 206 exteriorly near the rear ends thereof. The shaft 216 extends through a slot 218 in each side plate 206 to permit movement bodily longitudinally of the side plates 206. Suitable screws 219 of any well known type are mounted in brackets 220 secured to the side plates 206 and are in engagement with the adjustable bearing brackets 217 for adjustment thereof. A sprocket 222 is mounted on the shaft 212 adjacent each bearing 213, being secured to the shaft 212 by a setscrew, or the like, and an aligned sprocket 223 is secured to the shaft 216 adjacent each bearing 217, being secured to the shaft 216 by a setscrew, or the like. A continuous chain 225 is disposed about each pair of aligned sprockets 222 and 223. Transversely disposed rods 226 are secured at their ends to the chains 225 through suitable brackets 227 connected thereto and welded to selected links (Figs. 5, 6, and 28). The rods 226 are at right angles to the side plates 206 and to the chains 225 and are spaced a predetermined distance apart in order to successively pick up and push groups of partition strips 115 dropped from the hopper 56.

The upper disposed portions of the chains 225 move across the above-mentioned platform 66 which is disposed on the upper flanges of the side

plates 206 and extends between the sprockets 222 and 223 (Figs. 6 and 28). The platform 66 has side flanges 228 which serve as retaining guides for the chains 225.

The shaft 212 is preferably rotated by the motor (not shown) which powers the assembly machine with which the present feeding mechanism 52 is associated. A rotated shaft segment 239 is connected at one end to the shaft 212 by a conventional universal coupling 231 and at the other end by a conventional universal coupling 232 to a stub shaft within a bearing 233 (Figs. 1, 2, and 10). The drive mechanism 72 for transmitting the power from the main motor to the stub shaft in the bearing 233 and thence to the conveyor construction 64 is particularly described below.

Immediately forwardly of the conveyor construction 64 is the constant speed partition strip feed construction 68 and the step by step partition strip feed construction 70 which are mounted upon a composite frame 240 which comprises a U-shaped structural member 241 of angular cross section and extension members 242 of angular cross section secured to the U-shaped member 241 by a suitable bolt 243, or the like (Figs. 1, 2, 4, 13, 15, and 16). Each member 241 and 242 includes spaced aligned openings 244.

The constant speed partition strip feed construction 68 is mounted adjustably on the extension members 242 (Figs. 1, 2, 4, and 15). Specifically, a housing 245 of U-transverse cross section is mounted on the extensions 242, and includes a bottom wall 246 and side walls 247, each of the latter of which includes an upper horizontal flange 248. The bottom wall 246 extends outwardly beyond the side walls 247, the extensions being engaged by clamps 249 connected to the extensions 242 by suitable bolts 250 extending through selected apertures 244 (Figs. 4 and 15). The housing 245 is of the same cross section as the housing shown in Fig. 14 which is indicated by a like reference numeral. End plates 251 and 252 are secured by suitable bolts 253 to the ends of the housing 245. Segmental top plates 254 and 255 are secured by suitable bolts 256 to the flanges 248 of the housing 245. A driven shaft 257 is rotatably mounted in bearings 258 mounted in the end plate 251 and an intermediate plate 259 formed integral with or secured to the housing bottom wall 246 by welding, or the like. The driven shaft 257 is connected to a rotated shaft segment 260 by a conventional universal coupling 261, the shaft segment 260 being connected to a stub shaft disposed within an extended bearing 263 by a conventional universal coupling 264 (Figs. 1 and 9).

Three identical feed roller units 270 are mounted in the housing 245, the details of a single unit being illustrated in Figs. 18 through 21. Each feed unit 270 includes a housing 271 which preferably is a casting of the configuration clearly shown in Figs. 18 through 21 and includes a base portion 272, opposed mounting flanges 273 extending from the top edges of the base portion 272, and a vertical extension 277. The base portion 272 is formed with side walls 274 and a bottom web 275, the side walls 274 defining a chamber 276. Aligned apertures are formed in the web 275 and the vertical extension 277 which rotatably receive a shaft 278. A bevelled gear 279 is secured to the lowermost end of the shaft 278 by a suitable setscrew, or the like, adjacent the bottom face of the web 275. A feed roller 280 is secured to the upper end of the shaft 278 by a suitable pin 281, or the like. The roller 280 in-

cludes a knurled feed portion 282 which contacts a partition strip 115 in feeding engagement. The roller 280 abuts the upper end of the vertical extension 277. A pinion 284 is secured to the shaft 278 by a pin 285, or the like, interiorly of the chamber 276. A sleeve 287 extends into the chamber 276 and includes an integral base portion 288 which is pivotally mounted on a pin 289 supported by the walls 274 of the base portion 272. The base portion 288 has an opening 290 (Fig. 14) in which is disposed a pinion 291 secured to the lower end of a shaft 293 by a suitable pin 292 and in mesh with the pinion 284. The shaft 293 is rotatably mounted in the sleeve 287 and has a feed roller 295 secured to its upper end by a suitable pin 296, or the like. The feed roller 295 includes a knurled portion 297 which is in opposed relation to the knurled portion 282 of the feed roller 280. A tension spring 298 of coil type resiliently biases the sleeve 287 and its associated feed roller 295 towards the extension 277 and the feed roller 280, the spring 298 being anchored to sides of the extension 277 at its ends by suitable screws 300. As is manifest from Figs. 14 and 15, the flanges 273 are disposed on the flanges 248 of the housing 245 and are anchored in place by suitable bolts 301. Each bevelled gear 279 is in engagement with a bevelled gear 303 secured to the shaft 257 by a suitable pin 304, or the like. It is manifest that rotation of the shaft 257, which is preferably effected from the main motor which drives the assembly machine with which the present feed mechanism 52 is associated, will simultaneously continuously drive all six feed rollers of the feed construction 64.

The drive mechanism 72 through which the conveyor construction 64 and the constant speed partition strip feed construction 68 are actuated is best shown in Figs. 1, 2, and 7 through 10. An angle member 310 having a web 311 and upper and lower flanges 312 and 313, respectively, is mounted on spaced posts 315 and 316 by suitable bolts 317, each post 315 and 316 being mounted in pedestals 320 identical with the above described pedestals 76. Like the pedestals 76, the pedestals 320 are anchored to the foundation 80. A bearing 322 is secured to the web 311 near the front or left end (Figs. 2 and 7) by suitable screws 323 and rotatably receives a stub shaft 324 which is connected at its outer end to a conventional universal coupling 325, the other end of said coupling 325 being connected to a shaft 326 which is suitably connected to the motor (not shown) which drives the assembly machine with which the present feed mechanism 52 is associated. A pinion 328 is connected to the stub shaft 324 in adjacent relationship to the inner side of the web 311 by a suitable setscrew, or a pin. The pinion 328 is in mesh with a gear 330 secured to a stub shaft 331 by a suitable setscrew, or the like, the stub shaft 331 having bearing support in a sleeve 332 formed in the web 311 and being maintained in position by a nut 333 threaded onto a reduced threaded extension 334 of the stub shaft 331 (Fig. 8). A bevelled gear 336 is secured to or is formed integral with the gear 330 for rotation therewith which is in meshing engagement with a bevelled gear 337 (Fig. 1) secured to a shaft 338 by a setscrew, or the like. The shaft 338 is rotatably mounted in spaced bearings 339, four being shown, which may be any type of simple bearing welded or otherwise secured to the interior face of the web 311 and are shown as apertured block members. Manifestly, the shaft 338 is driven from the just described gear train.

Towards the rear end of the shaft 338, a bevelled gear 340 is secured by a setscrew, or the like, which is in mesh with a pinion 341 secured by a pin 342, or the like, to a stub shaft 343 rotatably mounted in the bearing 263 (Fig. 9). The bearing 263 is secured to the web 311 by suitable screws 344.

A bevelled gear 347 is secured to the shaft 338 by a setscrew, or the like, adjacent the rear bearing 339 (Fig. 1). In mesh with the bevelled gear 347 is a bevelled gear 348, which is formed integral with, or secured to for rotation with, a pinion 350 secured by a setscrew, or the like, to a stub shaft 351 mounted in a bearing sleeve 352 formed in the web 311 (Fig. 10). The stub shaft 351 is secured against removal by a nut 353 threaded onto a reduced threaded extension 354 of the stub shaft 351. In mesh with the pinion 350 is a pinion 356 secured by a setscrew, or the like, to the end of a stub shaft 357 connected to the universal coupling 232 and rotatably mounted in the bearing 233 secured to the web 311 by suitable screws 358.

The step by step partition feed construction 70 is best illustrated in Figs. 2, 4, 13, 16, 17, 26 and 27. The feed construction 70 includes a rear group 365 and a front group 366 of feed units 270 and drive mechanism 367 for actuating the same in step by step relation. As is manifest from a comparison of Figs. 13 and 16 with Fig. 15, the feed units of the two groups 365 and 366 are identical with the feed units 270 above described and, hence, no further description is necessary, and the same reference numerals are applied as are above used in conjunction with the previously described feed units 270. Furthermore, each group 365 and 366 of feed units 270 is mounted in a housing 245 identical with the housing 245 above described, and, hence, the same reference numerals are repeated, with the exception that the housing 245 incorporating the group 366 of feed units 270 includes a second intermediate wall 370 similar to the intermediate wall 259 (Fig. 16). The longitudinally extending portions of the U-shaped structural member 241 adjustably support the housings 245 of the feed construction 70 in the same manner as the housing 245 of the feed construction 68 is supported (above described). Both the feed groups 365 and 366 and the constant feed construction 68 are adjustable along the member 241 and the extensions 242 to accommodate partition strips of different lengths.

A driven shaft 371 is journaled in bearings 372 supported by the end plate 251 and the intermediate plate 259. Bevelled gears 373 are secured by suitable setscrews 374 to the shaft 371 in meshing relation with the bevelled gears 279 of the feed units 270. A bevelled gear 375 is secured on the inner end of the shaft 371 by a pin 376, or the like, the teeth of the bevelled gear 375 being disposed between the intermediate plate 259 and the end plate 252, and being in meshing engagement with a bevelled gear 377 (Figs. 13 and 17) secured to a stub shaft 378 extending through the side wall 247 of the rearward housing 245. The stub shaft 378 is secured by a coupling 379 to an enlarged hollow shaft segment 380 which telescopically receives one end of a shaft segment 381. A pin 385 is anchored in the shaft segment 381 and extends through diametrical slots 386 in the shaft segment 380 to permit adjustment. The shaft segment 381 is secured by a coupling 382 to a stub shaft 383 on the other end of which is secured a bevelled

gear 384 which has bearing support in the wall 247 of the forward housing 245 supporting the group 365 of the feed units 270.

Referring to Fig. 16, a driven shaft 387 is supported in bearings 388 mounted in the intermediate plates 370 and 259. Bevelled gears 389 are secured to the shaft 387 by suitable setscrews 390 in meshing engagement with the bevelled gears 279 of the feed units 270. On one end of the shaft 387 is secured a bevelled gear 392 by a suitable setscrew, or the like, which is in meshing engagement with the above-mentioned bevelled gear 384. It is manifest from the foregoing that the feed units 270 of the group 366 are driven at the same speed of and simultaneously with the feed units 270 of the group 365, since the bevelled gears in the gear train are all of the same size.

Referring to Figs. 2, 4, 13, 26, and 27, the drive mechanism 367 for the feed construction 70, in addition to the gear train just described, includes a one-way clutch mechanism 395, preferably of the simple ball or roller overrunning type, the reciprocating element of which is secured to a stub shaft 396 and the one-way driven member of which is secured to a stub shaft 397. The stub shaft 397 has bearing support in an intermediate wall 398 of a frame 399 which also includes end walls 400 and 401 and side walls 402. The end wall 401 is secured by suitable screws 403 to the U-shaped structural member 241 (Figs. 4 and 13). The stub shaft 397 is connected through two conventional universal connections 405 and 406 and an intermediate shaft segment 407 to the driven shaft 371. The stub shaft 396 is rotatably mounted in a bearing 409 supported in the end wall 400.

On the outer end of the stub shaft 396 is a brake 411 (Figs. 4, 13, and 27) which includes a disc member 412 secured to the stub shaft 396 by a key 413. Clampingly engaging the disc member 412 are opposed brake shoes 415 which are pivotally mounted on a pin 416 supported by and extending from the end wall 400. One shoe 415 has spaced ears 417 and the other shoe 415 a tongue 418, extending between the ears 417, pivotally received by the pin 416. Disc plates 420 of larger diameter than the disc member 412 are secured thereto by suitable bolts 421 which provide spaced annular guide flanges maintaining the brake shoes 415 against lateral movement. A U-shaped lever 425 is pivotally connected by rivet 426 to the upper end of one shoe 415 and straddles the upper portion thereof as is clear from Figs. 4 and 27. The lever 425 also straddles the upper portion of the other shoe 415 which is cut away to provide a shoulder 427. An adjusting screw 428 having a suitable operating handle 429 threadedly engages the bight of the U-shaped lever 425 and abuts the shoulder 427. A securing nut 430 maintains the screw 428 in selected position. It is clear that clockwise movement of the screw 428 will bring the shoes 415 together about the pivot pin 416 to tighten the braking engagement with the disc member 412, and that counterclockwise movement thereof will loosen the braking relationship.

A driven pinion 435 is secured to the stub shaft 396 by a key 436 between the end wall 400 and the clutch mechanism 395 (Figs. 4, 13 and 26). A gear sector 437 is in engagement with the pinion 435 and is pivotally mounted on a fixed short shaft 438 which threadedly engages an aperture in the intermediate wall 398 at one end and has support in the end wall 400 at the other end.

A suitable bushing 439 is press-fitted or otherwise secured interiorly of the hub of the gear sector 437. A suitable collar 440 maintains the gear sector in position to continue engagement with the pinion 435, being secured to the shaft 438 by a suitable setscrew 441. The gear sector has an integral arm 443 which extends downwardly from the hub thereof and which is pivotally connected at 444 to the bifurcated head of a connector member 445. The other end of the member 445 threadedly receives a rod 446 which is maintained in selected secured position by a suitable nut 447. The rod 446 is secured at its other end to an eccentric mounted on the partition assembly machine with which the present feeding mechanism 52 is associated, such eccentric being actuated by the motor of the partition assembly machine. Neither the eccentric nor motor are shown, but both are of conventional construction and are shown in the above-mentioned Vail and Dauber patent. It is manifest that reciprocal movement of the rod 446 will effect rocking movement of the gear sector 437, which movement will be transferred to the pinion 435 to rock the stub shaft 396. The one-way clutch 395 is effective to transmit only step by step movement in one direction to the shaft 371.

The partition strip guide construction 62 is best illustrated in Figs. 1, 2, 4, 11, 12, 14, 22 through 24, and 29. Extending forwardly from each vertical portion 197 and 203 of each plate 195 and 196, respectively, and spaced a short distance above the platform 66, is a narrow, long metal plate 450, each of which is secured to its respective plate portion by a rivet 451, or the like, which extends through an opening in the vertical plate portion and a suitable elongated slot 452 in the plate 450 (Fig. 29). As is clear from Figs. 1 and 2, the strip plates 450 are disposed in pairs and extend forwardly to and beyond the front edge of the conveyer construction 64. Each pair of plates 450 thus provides a partition strip passage 453. At its forward end, each strip plate 450 is suspended from a transversely disposed rod 455 by means of a hanger strap 456 (Figs. 1, 2, 11 and 12). A suitable nut, bolt and washer assembly 457 is received by an aperture in the plate 450 and a slot 458 in the strap 456. The head of the bolt of the assembly 457 is countersunk in the plate 450 in order to insure a smooth surface for uninterrupted passage of partition strips. Each hanger strap 456 is secured in selected position on the rod 455 by a setscrew 459. Hence, the vertical and lateral positions of the front ends of the plates 450 are adjustable. The slot 452 at the rear end of the plates 450 provides longitudinal adjustment. The rod 455 is supported at each end on a post 460, which is secured by suitable bolts 461 to the side plates 206 which support the conveyer construction 64. It is clear from Fig. 4 that each channel 453 defined by the strip plates 450 terminates forwardly adjacent a pair of feed rollers 295 of the constant speed partition strip feed construction 68.

The guide construction 62 includes duplicate pairs of plate segments 465 and 466 disposed forwardly of the feed rollers 295 of the constant speed feed construction 68, each pair defining a channel 467 which forms a continuation of a channel 453 (Figs. 4, 14, 22, and 24). As is clear from Fig. 4, each plate segment 465 is bowed slightly between its ends. Each plate segment 466 includes a double bend, as shown, which disposes the shorter forward portions of the three plate segments 466 substantially parallel with the

longitudinally extending elements of the feeding mechanism 52, and the longer rearward portions at an angle to the shorter forward portions. This configuration and arrangement of the plate segments 465 and 466 provides a construction which permits each succeeding partition strip 115 to overlap its preceding partition strip in feeding movement towards the partition assembly machine with which the present feeding mechanism 52 is employed. Each of the plate segments 465 and 466 is supported at its rear end by a post 470 threadedly engaging a flange 471 formed integral with the housing 271 of one of the feed units 270 of the constant speed feed construction 68, each housing 271 supporting a pair of posts 470 (Figs. 4 and 14). A supporting member 473 formed with an integral collar 474 at one end (Fig. 24) is secured to the rear end of each plate segment 465 and 466 by a U-shaped bracket 475 which is anchored to the respective plate segments 465 and 466 by suitable screws 476 (Figs. 14 and 22). The supporting members 473 are free to move longitudinally of the plate segments 465 or 466, but each has a close fit vertically with its bracket 475 to substantially eliminate vertical movement therebetween. The collar portion 474 of each member 473 slides over a post 479 and abuts a shoulder 478 thereof, each post 470 being of greater diameter below the shoulder 478. Each plate segment 465 and 466 is flared outwardly at the rear and conforms to the respective collar 474 to facilitate feeding of partition strips 115 therebetween. Each plate segment 465 and 466 is supported at its forward end on the rear feed units 270 of the feed construction 70 in the same manner as just described for the rear ends, the several elements of the supporting construction bearing the same reference numerals and requiring no further detailed explanation. Beneath each pair of plate segments 465 and 466 is a horizontally disposed plate 480 of U cross section which has bearing support on the flanges 471 of the housings 271 and is maintained in position by the posts 470 extending through suitable holes therein, as is clear from Fig. 14.

Forwardly of the plate segments 465 and 466 are pairs of plate segments 485 which define partition channels 486. Each pair of plate segments 485 is disposed between longitudinally spaced pairs of rollers 295 of feed units 270 of groups 365 and 366 of the step by step feed construction 70. Each plate segment 485 is curved outwardly at the rear end to facilitate entry of a partition strip. Each plate segment 485 is mounted at front and rear ends by supporting members 473 and other elements identical with the previously described elements supporting the rear ends of plate segments 465 and 466, these several elements bearing the same reference numerals and requiring no further explanation. A plate 487 of U cross section similar to the plates 480, but much shorter, is disposed beneath each pair of plate segments 485 and is supported in the same manner as the plates 480.

Forwardly of the front group 366 of feed units 270 is a transversely disposed plate 490 which is secured to the forward flanges of the housings 271 of the feed units 270 of the front group 366 by suitable screws 491 (Figs. 1, 4 and 46). Each screw 491 also adjustably secures in position a guide post 492 (Fig. 23), extending through a slot 493 formed in a horizontal portion 494 thereof. Each guide post 492 also includes a vertical portion 495 bevelled at 496 to facilitate passage between opposed guide posts of partition strips.

Manifestly, the plane of the plate 490 is in the same plane with that of plates 480 and 487.

In Figs. 45 through 48 is shown a preferred vertically adjustable supporting construction for the front end of the partition feeding mechanism 52 which is mounted on the rear of the partition assembly machine with which the present mechanism 52 is associated. A partition assembly machine 500 includes side plates 501 and 502, an end plate 503, a base member 504, and rear supporting members 505. A shaft 508 has bearing support in spaced brackets 509 secured to the end plate 503 by suitable bolts 510. A bevelled gear 511 is secured to one end of the shaft 508 by a suitable setscrew or pin, and a bevelled gear 512 is secured near the other end by a suitable setscrew or pin. Secured on the end of the shaft 508, remote from the bevelled gear 511, is an operating hand wheel 513. Each bracket 509 includes an integral collar 515 through which extends a vertically disposed threaded shaft 516. The shafts 516 rotate freely in the collars 515, each having secured to its lower end a bevelled gear 517 by a suitable setscrew or pin which are in engagement with the bevelled gears 511 and 512. Each shaft 516 threadedly receives a rider nut 518 which is welded at 519 to a vertically and transversely disposed plate 520. As is clear from Figs. 45 and 47, the plate 520 overlaps the rear edges of the side plates 501 and 502, each of which has a cutaway 522 receiving the plate 520. A strip 523 is secured to the rear edge of each side plate 501 and 502 by suitable screws 524 in overlapping position in respect to the cutaway 522 to maintain the plate 520 in position. Welded to each side of the plate 520 at 526 is an angle strap 527, to the horizontal portions of which is welded at 528 a platform 529 which is of the same elevation as the plate 490 and which is adapted to receive partition strips in edgewise position. The plate 529 is cut away in the upper edge to receive the free ends of the structural member 241, which are welded at 530, or otherwise secured to the plate 520 against accidental removal. Manifestly, rotation of the operating wheel 513 effects up or down movement of the plate 520 and its associated elements, dependent, of course, upon the direction of rotation of the wheel 513. This adjustment permits the disposition of the platform 529 at the desired level for the particular depth of partition strip being assembled.

Operation

The operation of the present automatic partition strip feeding mechanism 52 is quite simple, and when attached to a partition assembly machine such as that shown in the above-mentioned Vail and Dauber patent, requires only a single attendant to maintain it under full operation. An attendant need but start the partition assembly machine, and, therethrough the present mechanism 52, and then keep the instant mechanism 52 supplied with partition strips 115, which may be of the simple form shown in Fig. 49, or of any interlocking type. Manifestly, the present feeding mechanism 52 may be fed automatically as well as by hand.

The compartments 105 of the hopper 56 are supplied with partition strips 115. The stacks should be maintained at substantial levels in order to insure continuous feeding operation, although the height of the stacks is not of importance. Three compartments 105 are shown, although additional compartments may be employed if desired. In fact, in a further develop-

ment of the present machine, five compartments are used which manifestly materially increases the output of the combined partition assembly machine and feeder mechanism 52.

Assuming that the compartments 105 are supplied with partition strips 115, and that an air supply is available for operation of the shaft 143, it is but necessary to start the motor of the partition assembly machine with which the mechanism 52 is associated to begin the feeding operation, it being clear from the above-detailed description that the conveyer construction 64, the constant speed partition feed strip construction 68, and the step by step partition feed construction 70 are driven by the motor of the partition assembly machine.

Upon actuation of the conveyer construction 64, its transversely disposed rods 226 are moved by the continuous chains 225 in the path clearly indicated in Fig. 28. As a rod 226 passes beneath the shoe 187, the plunger 176 of the air valve 173 is moved upwardly to permit air under pressure from the supply line 175 to pass into the valve 173 and thence by the supply line 171 into the air cylinder 169 (Figs. 32 and 33). The air admitted into the valve 169 effects movement of the plunger 168 to the left (Fig. 35), which moves the shaft 143 to the left against the action of the return spring 152. As is clear from Figs. 37 and 38, movement of the shaft 143 to the left effects pivotal movement of each of the rocker arms 138 to the left as viewed in Figs. 35 and 37. Each shaft 113 is therethrough rocked to effect similar rocking movement of its supported actuating members 132 (Figs. 38 and 39). Viewing Fig. 39, it is manifest that rocking movement of the actuating members 132 to the left effects movement to the left of the blades 117, the right hand of each of which, when considering a single compartment 105, moves the bottommost partition strip 115 to the left into the space formerly occupied by the left hand blade 117. It is understood, of course, that each stack of partition strips 115 rests upon the respective supporting plates 123. It is to be noted that each laterally moved partition strip 115 drops down at its free edge into about the position shown in Fig. 39 in full lines.

The particular rod 226 passes beyond the shoe 117 whereupon it drops back to the position of Fig. 32, releasing the plunger 176 and closing the air valve 173. Thereupon, the air valve 173 and the cylinder 169 exhaust, which permits the spring 152 to return the shaft 143 to its initial position of rest. This movement rocks the rocker arms 138 to the right when viewed in Figs. 35 and 37, which, in turn, rocks the shaft 113 and the supported actuating members 132. Again viewing Fig. 39, it is clear that rocking movement of the actuating members 132 to the right will discharge the bottommost partition strip 115 of each compartment 105 onto the partition strip edgewise disposing construction 68. The right longitudinal edge of each partition strip 115 strikes the horizontal portion 262 of the plate 196 therebeneath, whereupon the other longitudinal edge will descend first into the space between the plates 195 and 196 to dispose the partition strip 115 in edgewise position.

The conveyer construction 64 is so timed that a rod 226 immediately contacts the rear edges of the partition strips 115 of a dropped group and moves the strips forwardly into the channels 453. The three partition strips 115 are moved forwardly as a group until the forward

edges are moved into engagement with the constantly rotating feed rollers 295 of the constant speed partition strip feed construction 68. These feed rollers 295 are moved at a rate of speed which will impart an accelerated movement to the partition strips 115 and will move them forwardly into the channels 467 until they are fed into engagement with the feed rollers 295 of the feed units 270 of the rear group 365 of the step by step feed construction 70. The distance between the two groups of feed rollers 295 is less than the length of a partition strip so that the partition strips 115 are always in positive engagement by one or the other or both groups of feed rollers 295. The last-mentioned feed rollers 295 move the partition strips 115 forwardly in a step by step manner into engagement with the feed rollers 295 of the front group 366 of feed units 270 which feed the partition strips 115 through the guide posts 492 and onto the platform 529 and into and through the assembly zone where transverse partitions are disposed across them by such mechanism as that shown in the Vail and Dauber assembly machine of the above-mentioned patent.

It is to be observed that, as the partition strips 115 pass the bend in the plate segments 466, the rear end of each is moved into position substantially against the forward portion of the plate segment 466 so that the forward portion of a succeeding partition strip 115 may pass the rear end thereof in overlapping relation therewith. The relative movement of the several feed rollers 295 of the step by step feed construction 70 and the constant speed feed construction 68 is such that the overlapping will amount to exactly an amount to insure the feeding into the assembly zone of constantly spaced aligned notches which manifestly increases the output over end to end feeding of partition strips into the assembly zone. Overlapping per se is not novel with the applicant, but the feature is important in connection with the operation of the present machine.

The step by step partition strip feed construction 70 is, of course, timed to feed the partition strips 115 into the assembly zone of the assembly machine in accordance with the feeding of the transverse strips by the assembly machine. The feeding action of the several feed wheels 295 is positive so that it is but necessary to adjust the stroke of the rod 446 when it is desired to increase or decrease the length of the feeding step, which is necessary when partition strips of different lengths are employed. The positions of the feed roll groups 365 and 366 are adjusted on the member 241 to accommodate strips of different lengths.

It is unnecessary to go into further detailed description of the operation of the several units which make up the feed constructions 68 and 70, or set out a more detailed operation of the several parts of the conveyer construction 64 and the partition strip release mechanism 58 in view of the detailed description above.

It is manifest that there has been provided a feed mechanism for partition strips which fulfills the objects and advantages sought therefor.

It is to be understood that the foregoing description and the accompanying drawings have been given by way of illustration and example. It is also to be understood that changes in form of the several parts, substitution of equivalent elements or steps, and rearrangement of parts or steps, which will be readily apparent to one skilled in the art, are contemplated as within the scope of

the present invention which is limited only by the claims which follow.

What is claimed is:

1. Feeding mechanism for a partition assembling machine comprising means for holding at least one stack of preformed partition strips above an open space, means for releasing the bottom strip of a stack of preformed partition strips held within said holding means to permit it to fall freely downwardly into such open space, means for deflecting released strips into edge-wise positions as they fall freely downwardly, means for supporting the released strips in edge-wise positions, means for maintaining strips in edge-wise positions and for guiding the same into predetermined spaced relation, and means for advancing edge-wise disposed strips towards a partition assembly zone.
2. Feeding mechanism for a partition assembling machine comprising means for holding spaced stacks of preformed partition strips, means for releasing the bottom strip of stacks of preformed partition strips held within said holding means, means for deflecting released strips into edge-wise positions, means for maintaining strips in edge-wise positions and for guiding the same into predetermined laterally spaced relation, means for advancing edge-wise disposed strips towards a partition assembly zone at a substantially constant speed, and means for advancing edge-wise disposed strips into and through a partition assembly zone in a step by step movement.
3. Feeding mechanism for a partition assembling machine comprising means for holding spaced stacks of preformed partition strips, means for releasing the bottom strips of stacks of preformed partition strips held within said holding means, means for deflecting released strips into edge-wise positions, means for maintaining strips in edge-wise positions and for guiding the same into predetermined laterally spaced relation, means for advancing strips through an assembly zone, means for advancing strips into position for engagement by said first advancing means and guide means permitting movement of advancing strips into overlapping relation with the immediately previously advanced strips, and means for actuating said advancing means.
4. In a feeding mechanism for a partition assembling machine, guide means for directing laterally spaced edge-wise disposed preformed partition strips towards and into a partition assembly zone, means for advancing strips through an assembly zone, means for advancing strips into position for engagement by said first advancing means and guide means permitting movement of such advancing strips into overlapping relation with the immediately previously advanced strips, and means for actuating said advancing means.
5. In a feeding mechanism for a partition assembling machine, guide means for directing laterally spaced edge-wise disposed preformed partition strips towards and into a partition assembly zone, first rotatable rollers for advancing strips through an assembly zone, second rotatable rollers for advancing strips into position for engagement by said first advancing rollers and guide means permitting movement of such advancing strips into overlapping relation with the immediately previously advanced strips, and separate means for actuating said advancing rollers.
6. In a feeding mechanism for a partition assembling machine, means for holding spaced stacks of preformed partition strips, means for

releasing the bottom strips of stacks of preformed partition strips held within said holding means, means for deflecting released strips into edge-wise positions, means for maintaining strips in edge-wise positions and for guiding the same into predetermined laterally spaced relation, means for advancing edge-wise disposed strips towards a partition assembly zone, including spaced transverse members mounted for endless travel adapted to engage the rear edges of spaced edge-wise disposed strips and to move the same predetermined distances, said strip releasing means including actuating construction successively engageable by said transverse members for effecting strip release in timed relation to the travel of said members, a second means for advancing edge-wise disposed strips towards a partition assembly zone including partition strip engaging rotatable rollers and means for rotating them at constant speed, and means for advancing edge-wise disposed strips through a partition assembly zone including partition engaging rotatable rollers and means for rotating them in step by step movement to feed partition strips through the partition assembly zone in a manner to receive transverse strips when substantially at a standstill.

7. In a feeding mechanism for a partition assembling machine, guide means for directing spaced preformed partition strips towards and into a partition assembly zone, first rotatable rollers for advancing strips through an assembly zone, second rotatable rollers for advancing strips into position for engagement by said first advancing rollers and guide means permitting movement of such advancing strips into overlapping relation with the immediately previously advanced strips, separate means for adjusting said first and second rotatable rollers longitudinally of advanced strips, and separate means for actuating said advancing rollers.

8. Feeding mechanism for a partition assembling machine comprising means for holding spaced stacks of preformed partition strips, means for releasing the bottom strips of stacks of preformed partition strips held within said holding means, means for deflecting released strips into edge-wise positions, means for maintaining strips in edge-wise positions and for guiding the same into predetermined laterally spaced relation, means for advancing edge-wise disposed strips towards and into a partition assembly zone, and means for adjusting said advancing means vertically in respect to the associated partition assembling machine to permit feeding preformed partition strips of different selected depths.

9. In a feeding mechanism for a partition assembling machine, guide means for directing spaced preformed partition strips towards and into a partition assembly zone, first pairs of rotatable rollers for advancing strips through an assembly zone, second pairs of rotatable rollers for advancing strips into position for engagement by said first advancing rollers and guide means permitting movement of such advancing strips into overlapping relation with the immediately previously advanced strips, the several pairs of rollers receiving edge-wise preformed partition strips between them for advancing the same, and separate means for actuating said advancing rollers.

10. In a feeding mechanism for a partition assembling machine, guide means for directing spaced preformed partition strips towards and

into a partition assembly zone, first pairs of rotatable rollers for advancing strips through an assembly zone, second pairs of rotatable rollers for advancing strips into position for engagement by said first advancing rollers and guide means permitting movement of such advancing strips into overlapping relation with the immediately previously advanced strips, the several pairs of rollers receiving edge-wise preformed partition strips between them for advancing the same, one roller of each pair being spring biased towards the other roller to firmly engage a preformed partition strip, and separate means for actuating said advancing rollers.

11. Feeding mechanism for a partition assembling machine comprising means for holding spaced stacks of preformed partition strips, means for releasing the bottom strip of stacks of preformed partition strips held within said holding means, means for deflecting released strips into edge-wise positions, means for maintaining strips in edge-wise positions and for guiding the same into predetermined laterally spaced relation, means for advancing edge-wise disposed strips towards a partition assembly zone at a substantially constant speed, means for advancing edge-wise disposed strips into and through a partition assembly zone in a step by step movement, and means for driving both of said advancing means and for actuating said release means from the power means of the partition assembling machine with which said feeding mechanism is associated.

12. In a feeding mechanism for a partition assembling machine, means for holding spaced stacks of preformed partition strips, means for releasing the bottom strips of stacks of preformed partition strips held within said holding means, means for deflecting released strips into edge-wise positions, means for maintaining strips in edge-wise positions and for guiding the same into predetermined laterally spaced relation, means for advancing edge-wise disposed strips towards a partition assembly zone, including spaced transverse members mounted for endless travel adapted to engage the rear edges of spaced edge-wise disposed strips and to move the same predetermined distances, said strip releasing means including actuating construction successively engageable by said transverse members for effecting strip release in timed relation to the travel of said members, a second means for advancing edge-wise disposed strips towards a partition assembly zone including pairs of rollers disposed to receive preformed partition strips between them, and means for advancing edge-wise disposed strips through a partition assembly zone including pairs of rollers disposed to receive preformed partition strips between them.

13. Feeding mechanism for a partition assembling machine comprising means for holding spaced stacks of preformed partition strips, means for releasing the bottom strips of stacks of preformed partition strips held within said holding means, means for deflecting released strips into edge-wise positions, means for maintaining strips in edge-wise positions and for guiding the same into predetermined laterally spaced relation, means for advancing edge-wise disposed strips towards and into a partition assembly zone, means for adjusting said advancing means vertically in respect to the associated partition assembling machine to permit feeding preformed partition strips of different selected depths, and means for adjusting said advancing means lon-

5 longitudinally of fed strips to permit feeding preformed strips of different selected lengths.

14. Feeding mechanism for feeding preformed partition strips to a partition assembling machine comprising a frame including a plurality of compartments for receiving and holding spaced stacks of preformed partition strips, a chamber beneath each compartment, means for releasing the bottom strip only of stacks of strips to permit them to drop by gravity toward said chambers, means for deflecting released strips into edgewise positions, means for maintaining strips in edgewise positions and for guiding the same into predetermined spaced relation, and means for advancing edgewise disposed strips towards a partition assembly zone of a partition assembling machine.

15. Feeding mechanism for feeding preformed partition strips to a partition assembling machine comprising a frame including a plurality of compartments for receiving and holding spaced stacks of preformed partition strips, a chamber beneath each compartment, means for initially releasing one side of the bottom strip only of stacks of strips to permit sagging, means for subsequently releasing the other sides of sagging strips to permit them to fall by gravity at an angle to the horizontal, means for deflecting released strips into edgewise positions, means for maintaining strips in edgewise positions and for guiding the same into predetermined spaced relation, and means for advancing edgewise disposed strips towards a partition assembly zone of a partition assembling machine.

16. Feeding mechanism for feeding preformed partition strips to a partition assembling machine comprising a frame including a plurality of compartments for receiving and holding spaced stacks of preformed partition strips, a chamber beneath each compartment, means for releasing the bottom strip only of stacks of strips to permit them to drop by gravity including a reciprocably mounted blade disposed at the bottom of each compartment adapted to engage the bottom partition strip of a stack of strips and to move the same a predetermined distance horizontally, means for reciprocating said blades, means for deflecting released strips into edgewise positions, means for maintaining strips in edgewise positions and for guiding the same into predetermined spaced relation, and means for advancing edgewise disposed strips towards a partition assembly zone of a partition assembling machine.

17. Feeding mechanism for feeding preformed partition strips to a partition assembling machine comprising a frame including a plurality of compartments for receiving and holding spaced stacks of preformed partition strips, a chamber beneath each compartment, means for releasing the bottom strip only of stacks of strips to permit them to drop by gravity including reciprocably mounted blades disposed at the bottom of each compartment adapted to engage the bottom partition strip of a stack of strips and to reciprocate the same predetermined distances horizontally, means for reciprocating said blades, means for deflecting released strips into edgewise positions, means for maintaining strips in edgewise positions and for guiding the same into predetermined spaced relation, and means for advancing edgewise disposed strips towards a partition assembly zone of a partition assembling machine.

18. Feeding mechanism for feeding preformed

partition strips to a partition assembling machine comprising hoppers for receiving and holding stacks of preformed partition strips, means for adjusting the widths of said hoppers, means in each hopper for directing the lower portion of a stack of partition strips into snug relation with the defining walls, means at the bottom of each hopper for engagement by the longitudinal edges of the bottom partition strip of a stack, means for sliding the bottom strip of a stack sideways in one direction to release one side and in the other direction to release the other side to free such bottom strip from the stack, means for deflecting released strips into edgewise positions, means for maintaining strips in edgewise positions and for guiding the same into predetermined spaced relation, and means for advancing edgewise disposed strips towards a partition assembly zone of a partition assembling machine.

19. Feeding mechanism for feeding preformed partition strips to a partition assembling machine comprising hoppers for receiving and holding stacks of preformed partition strips, means for adjusting the widths of said hoppers, means in each hopper for directing the lower portion of a stack of partition strips into snug relation with the defining walls, means at the bottom of each hopper for engagement by the longitudinal edges of the bottom partition strip of a stack, means for sliding the bottom strip of a stack sideways in one direction to release one side and in the other direction to release the other side to free such bottom strip from the stack, an opening beneath said directing means for receiving a bottom strip in its sliding movement in said one direction, means for deflecting released strips into edgewise positions, means for maintaining strips in edgewise positions and for guiding the same into predetermined spaced relation, and means for advancing edgewise disposed strips towards a partition assembly zone of a partition assembling machine.

20. Feeding mechanism for feeding preformed partition strips to a partition assembling machine comprising hoppers for receiving and holding stacks of preformed partition strips, means for adjusting the widths of said hoppers, means in each hopper for directing the lower portion of a stack of partition strips into snug relation with the defining walls, means at the bottom of each hopper for engagement by the longitudinal edges of the bottom partition strip of a stack, means for sliding the bottom strip of a stack sideways in one direction to release one side and in the other direction to release the other side to free such bottom strip from the stack including reciprocable partition strip engaging members and actuating means therefor including a reciprocable shaft spring biased in one direction and power moved in the other direction, means for deflecting released strips into edgewise positions, means for maintaining strips in edgewise positions and for guiding the same into predetermined spaced relation, and means for advancing edgewise disposed strips towards a partition assembly zone of a partition assembling machine.

21. Feeding mechanism for feeding preformed partition strips to a partition assembling machine comprising a frame including a plurality of compartments for receiving and holding spaced stacks of preformed partition strips, a chamber beneath each compartment, means for releasing the bottom strip only of stacks of strips to permit them to drop by gravity including a reciprocably

mounted blade disposed at the bottom of each compartment adapted to engage the bottom partition strip of a stack of strips and to move the same a predetermined distance horizontally, means for reciprocating said blades including an air cylinder for moving said blades in one direction and spring means for moving said blades in the other direction, means for deflecting released strips into edgewise positions, means for maintaining strips in edgewise positions and for guiding the same into predetermined spaced relation, and means for advancing edgewise disposed strips towards a partition assembly zone of a partition assembling machine.

22. A feeding mechanism for a partition assembling machine comprising, guide means for directing laterally spaced edgewise disposed partitions towards and into an assembly zone of a partition assembly machine, a step by step partition feed construction for feeding guided laterally spaced edgewise disposed partitions to and through an assembly zone, and a constant speed partition feed construction for feeding guided laterally spaced edgewise disposed partitions to said step by step partition feed construction.

23. The partition feeding mechanism of claim 22 in which said step by step partition feed construction comprises two separate partition feeding units disposed in tandem and spaced longitudinally of the direction of feed, means supporting each unit for individual adjustment as a whole longitudinally of the direction of feed, and means for simultaneously actuating said units for feeding partitions to and into an assembling zone.

24. The partition feeding mechanism of claim 22 in which said constant feed construction comprises a unit adjustable as a whole longitudinally of the direction of feed, said unit being supported in tandem with said step by step partition feed construction.

25. The partition feeding mechanism of claim 23 in which each unit includes a plurality of laterally spaced pairs of partition feed rollers, means for simultaneously positively rotating both rollers of each pair, and means biasing one roller of each pair towards engagement with the other roller.

26. The partition feeding mechanism of claim 22 in which both said step by step partition feed construction and said constant speed partition feed construction include laterally spaced pairs of power driven rollers, each pair of rollers being feedingly engageable with partitions.
